UNITED STATES PATENT OFFICE.

WILLIAM C. LORING, OF HARTFORD, AND CHARLES E. JACOBSON, OF MANCHESTER, CONNECTICUT, ASSIGNEES TO A. F. WAY COMPANY, INCORPORATED, OF HARTFORD, CONNECTICUT, A CORPORATION OF CONNECTICUT.

METAL-WORKING MACHINE.

1,338,456.

Specification of Letters Patent. Patented Apr. 27, 1920.

Application filed August 22, 1919. Serial No. 319,169.

To all whom it may concern:

Be it known that we, WILLIAM C. LORING and CHARLES E. JACOBSON, citizens of the United States, residing at Hartford and 5 Manchester, in the county of Hartford and State of Connecticut, have invented certain new and useful Improvements in Metal-Working Machines, of which the following is a specification.

This invention relates to metal-working machines. The fundamental object of the invention is the provision of several mechanisms or as they might be considered, a plurality of machines combined in one unit, although it will be understood that when they are so combined or associated they lose their identity as machines, although they individually perform the respective functions of such machines. Said mechanical elements 15 or mechanisms may be of any suitable nature, for instance one may function as a lathe, another as a milling-machine and still another as a drill-press. As will be clear the mechanisms might be of some other 20 character, although we have combined in one unit, a machine capable of exercising respectively the functions of a lathe, a milling-machine, and a drill-press. It is conceivable that the sub-mechanisms of the several which are associated in a unit, may be utilized to secure other results; it is also conceivable that we may employ in conjunction 25 with a milling mechanism, a lathe mechanism and a drill-press mechanism, a mechanism of a kind different from the other three mechanisms or the mechanisms 30 identified by name. The invention as may be inferred comprises certain broad relations.

In the drawings accompanying and forming a part of the present specification we have fully shown one of the several forms of embodiment of the invention which, to enable those skilled in the art, to practice 40 the same will be set forth fully in the following description. We are not limited to this disclosure as we may depart therefrom in several respects within the scope of the invention defined by the claims following 45 said description.

Referring to said drawings:

Figure 1 is a perspective view as seen practically from the front of a machine involving the invention.

Fig. 2 is a like view as seen from an end 55 or side, for example the left side or end of Fig. 1.

Fig. 3 is a vertical transverse section of the machine.

Fig. 4 is a transverse section on the line 60 4—4 of Fig. 3, looking in the direction of the arrows.

Fig. 5 is a transverse section on the line 65 5—5 of Fig. 3, looking in the direction of the arrows.

Figs. 6, 7, 8, and 9 are cross sections on the lines 6—6, 7—7, 8—8 and 9—9 respectively of Fig. 4 the arrows indicating the points of view.

Fig. 10 is a detail view of certain driving mechanism.

Like characters refer to like parts throughout the several views which are on different scales.

The machine which we have selected for 75 illustration, is triplex in function. It is adapted to carry into effect the operations of a milling-machine, a lathe, and a drill-press as will be readily understood, these being merely three of many examples. As a 80 matter of fact it may not always be necessary to employ three and there may be instances where a less or a larger number may be employed. The plurality of mechanisms may be operated simultaneously or separately as desired by the user of the machine. Obviously we secure in a unit all the advantages of several distinct classes of metal-working mechanisms.

The framework for carrying the different 90 parts of the machine may be of any suitable character. As shown, it comprises a base or bed as 3, and a column or pedestal as 4, the two parts being rigidly united in some convenient manner as is common in various 95 metal-working machines, and both desirably being hollow or chambered to incase and inclose certain of the operative parts of the machine. This framing is best shown in Figs. 1 and 2 and it also appears in other 100 views.

There is necessarily a driver or motor from which as desired one or more of the separate mechanisms receives its or their motions. This driver or motor might take 105 any one of the several forms, the shaft 5 (Figs. 3 and 4) for instance being shown for the purpose. Although this shaft 5 is as

we indicate, a driving means or motive means, yet it in turn necessarily has to be driven in some convenient manner. This effect we can produce in many different ways as will be clear, although a belt drive meets our conditions. Above this driving shaft 5, as we have considered it, is a shaft as 6 which may be considered as the prime motor. This shaft 6 is tubular or hollow as shown best in Fig. 4 and it is supported as will later appear, by a bearing as 7 rising from the base or bed 3. Said tubular shaft 6 receives within it, the inner ends of a lathe-spindle as 8 and a milling mechanism spindle as 9. The bearing 7 to which we have referred, has depending portions 10 and 11 which constitute bearings or sustaining means for the two co-axial spindles 8 and 9, there being between these bearings 15 10 and 11, bearings 12 and 13 rising from the base or bed and which sustain the intermediate portions of the spindles 8 and 9 respectively all as shown clearly in Fig. 4. The bearing 10 and 12 to which we have referred act really as the head stock of the lathe mechanism of the machine, while the bearings 11 and 13 act similarly as the support for the spindle 9 of the milling mechanism as shown for instance in Fig. 4, and 20 25 30 arbor or spindle 14 as shown in Fig. 1.

This arbor 14 as will be understood, carries a cutter or a gang of cutters as is usual in milling machines, the cutter or cutters acting on the work which is clamped to a reciprocating table hereinafter described in a manner familiar to those versed in the metal-working art. The bearing end of this arbor 14 is supported by an overhanging arm as 15 which extends from the bearing 7 as shown in Figs. 1 and 4. The chuck or work holder 16 which is common in lathes, is connected with the nose or bearing end of the spindle 8. The inner ends of the two spindles 8 and 9 are closely arranged as 35 40 45 shown in Fig. 4 and they adjoin and support the tubular shaft 6. The driver or pulley 17 is shown as mounted upon the hollow shaft 6 in Fig. 4 which driver may be suitably driven as by a belt (not shown). As represented, the hub of the driver or pulley 17 has a lateral extension 18 to which is 50 55 60 keyed or otherwise suitably fastened, a power-transmitting member such as a pulley 19, connected as by the belt 20 with the driven member 21, (Fig. 3) which is also shown as a pulley fixed in some convenient way to the shaft 5. It will be clear that when the pulley 17 is rotated it acts through the intermediate described parts, to rotate 65 70 75 the driving or main shaft 5 which is entirely separately operative from the spindles 8 and 9 as shown. Said spindles 8 and 9 are adapted to be operatively connected with the said shaft 5 for action thereby as we will 80 85 90 hereafter explain.

The tail stock of the lathe mechanism is denoted by 22 and it is adjustable on the extension 23 of the base or bed 3 as common in lathes. Between what might be considered as the head stock 10, and the tail 70 stock 22 is mounted the carriage or slide 24, equipped with the usual accessories quite common in lathes. The lead-screw of the lathe portion or mechanism, is designated by 25 and it functions with the usual adjuncts on the carriage or slide 24, as customary in lathes of the ordinary type.

The automatic action of the lathe is brought about by a feed shaft as 26. This feed shaft, as a matter of fact, is common in 80 lathes, so that it is not necessary for us to describe the way in which it is associated with the carriage or slide 24, to effect the automatic traverse thereof. It will be understood of course that on the operation of 85 the feed shaft 26, the carriage or slide is advanced or retracted in accordance with the direction in which the shaft 26 is turned. The rear ends of the lead screw 25 and the feed shaft 26, as shown (Fig. 5) extend into 90 the box or casing 27.

We have represented as feathered or splined to the shaft 26 for movement longitudinally on said shaft, a spur gear as 28 which co-operates with an intermediate spur 95 gear 29 adapted to co-act with any of the sections of the cone gear 30, fixed to the extension of the lead screw 25. The several gears and co-operating parts which we are now describing are inclosed in the casing 100 or box 27, which as will be understood, is rigid with the frame 3 of the machine. An idler gear as 29 is rotatively supported as shown by the lever 31, fulcrumed on the feed shaft 26 within the box 27, the handle 105 or upper end of the lever projecting through a slot 32 in the top of the box. By manipulating this lever 31 the idler gear 29, can be thrown into mesh within any desired one of the sections of the cone gear 30, as 110 common in lathes. The feed shaft 26 therefore receives its motion from the lead screw 25, which is in turn rotated in some convenient manner, one way of accomplishing which we will now set forth.

There is shown, as fastened to the lead screw 25 in the box 27, the bevel gear 33 in mesh with the bevel-gear 34, fastened to the shaft 35, it being understood that the bevel-gear 33 is rigid with the lead screw 25. 115 The shaft 35, in addition to rigidly carrying the bevel gear 34, has at its rear or inner end (Fig. 3) the bevel gear 36 in mesh with the bevel gear 37 fastened to the shaft 38 (Fig. 4), which as shown, is parallel with 120 what we have considered the main shaft 5. It will, therefore, be clear that on the rotation of the shaft 38 the lead screw 25 and the feed shaft 26 through the intermediate connections, will be simultaneously rotated 130

to perform their respective functions. As shown the shaft 38 is co-extensive and practically parallel with the main shaft 5. In Fig. 4 and Figs. 6 to 9 inclusive, we have shown gearing by which the shaft 38 can be advanced at different speeds and also reversed. Owing to the fact that the rotation of the shaft 38 can be accomplished in opposite direction it follows that the carriage or 10 slide 24 can be reciprocated.

The trains of gears shown (Figs. 6, 7 and 8) as we will later set forth, are intended to advance at the will of the operator, the carriage or slide toward the headstock in 15 Fig. 1, the train of gears shown in Fig. 9, being intended to effect a backward movement of the carriage or slide 2. The trains of gears shown in these several Figs. 6 to 9 inclusive, will cause the reciprocation of 20 the carriage or slide 24. Their fundamental purpose however, is to effect variations in movement of the spindle 8, to which it will be remembered the chuck 16 is rigidly connected. We obtain variation in velocity 25 between the feed shaft 26 and the spindle 8 by shifting the gear 29, so as to bring it into mesh with any desired section of the cone gear 30. Obviously the shaft 38 is connected with the lathe spindle 8 in some 30 convenient way, belt gearing being shown for the purpose. The shaft 38 has fastened to it a pulley as 39, over which a belt as 40 is placed, this belt also passing around the pulley 41, keyed or otherwise fastened 35 to the lathe spindle 8.

The shaft 5 (Fig. 6) is shown connected to the shaft 38 by a train of gears of spur type, each as a matter of convenience being designated by 42. These gears 42 are intended to effect through the intermediate 40 described parts, the rotation of the shaft 38 at its maximum speed and the consequent maximum speed of the spindle 8. The gears of the intermediate speed train are each for 45 the same reason denoted by 43, and they are of spur type also. The gears of the low speed train, also of the same type, are designated by 44. Any one of the three trains to which we have just referred, is 50 put into or out of action by the movement laterally of the members of one of these trains. We have shown (Fig. 1) a lever as 55 by which this movement of a selected gear in any one of the three trains may be accomplished, and the same lever is also utilized for throwing into or out of action the gears 46 (Fig. 9) of the reverse train shown in Fig. 9. At will therefore, the lathe spindle 8 may be rotated forward at 60 different speeds or velocities, or may be reversed while changes in speed may be independently secured with respect to the carriage or slide 24.

The main shaft 5 (Figs. 3 and 4) as 65 shown, has fastened to it in some suitable

way, the bevel gear 47 in mesh with the bevel gear 48 fastened as represented to the lower end of the inclined shaft 49, supported at its lower extremity, by bearings on the frame and at its upper end extending 70 into a box as 50 (Fig. 3) on the column 51, rising from the framework 3. The shaft 49, as illustrated, has fastened to its upper end, within the box or casing 50, the driver 75 52, shown as a spur gear, and in constant mesh with a driven gear 53 on the jack-shaft 54, mounted in the box or case 50. There is splined to this jack-shaft 51 a series of gears each denoted by 54'; of different diameters and which are adapted to be 80 moved longitudinally of said jack-shaft 54, to put them into mesh with coöperating gears 55, on the shaft 56 the lower end of which is spaced from the upper end of the shaft 49, but is coaxial therewith. The 85 shaft 56 can therefore, as will be seen, through one of the sets of gears 54, be driven at different speeds to effect through coacting mechanism, corresponding movements of the spindle 57 (Fig. 3) of the drill 90 press portion of the machine. As represented, the shaft 56 is connected by meshing miter gears 58 with the stub shaft 59 rotatively supported at the upper end of the arm 60, rising from the upright or column 95 51, the front end of the shaft 59 being connected as by bevel gears denoted in a general way by 61, with the upper end of the spindle 57, which has the usual adjustments, and which may be provided with the customary 100 means for carrying a drill or other tool.

The milling mechanism spindle 9, may in like manner receive its motion in any convenient manner, although what might be considered its primary source, is a power 105 transmitting member in the form of a shaft 62, (Fig. 3). This shaft 62 is adapted to be driven forward at different speeds, or reversed at will, as we will later explain, although it is proper at this time to observe 110 that the rotation of said shaft 62 is brought about from the primary or main shaft 5, through meshing gears arranged in trains for the purpose, and shown in detail in Figs. 6 and 9 inclusive. The shaft 62 (see Figs. 115 3 and 4) has a belt connection with the milling mechanism spindle 9. As represented, said shaft 62 has fastened to it the pulley 63 connected as by the belt 64 with the pulley 65 fastened to the milling mechanism 120 spindle 9, so that it follows that when the shaft 62 is rotated, the spindle 9, will be also rotated, its speed, or direction of movement, depending on which one of the trains of gears (Figs. 6 to 9) is in action.

The shaft 5 (Fig. 6) is connected by a train of meshing gears as 66 with the shaft 62 the initial gear of said train being also the initial gear of the train 42. This train of gears 66 is what is utilized to drive the 130

shaft 62, and hence the spindle 9 at its maximum speed. In Fig. 7 we have shown between the shaft 5 and the shaft 62 the intermediate train of gears 67, the initial gear of which as in the other case is utilized in the train of gears 44. In Fig. 8, we have shown the low speed train for the spindle 9, the gears of which are denoted by 68, the first gear of this train being common to the 10 train 45 already described. This train of gears 68 is what is utilized to rotate the spindle 9 at its low speed. The gears of the reversing train (Fig. 9) are denoted by 15 69, and they are driven from a primary on the shaft 5. The several trains of gears shown in said Figs. 6, 7, 8 and 9, by which the spindle 9 is driven forwardly at variable 20 velocities or reversed, are thrown selectively into action through suitable means, acting on one of the gears of each train.

We have shown in Fig. 2 a reciprocatory table as 70 of the milling mechanism. This in practice will be equipped with means of some convenient kind to bolt, fasten, or otherwise hold work thereto which is being milled by the cutter, fastened to the arbor 14. This table is reciprocated through suitable agencies receiving their motion from the shaft 71, arranged at an inclination, and 25 having as represented, fastened to its lower end a bevel gear 72 in mesh with the bevel gear 73, which with the companion gear 74 is fastened to a stub shaft 75, the several 30 gears and stub shaft being carried in a box 76 which raises and lowers with the work carrying table 70 as the same is adjusted up and down. The bevel gear 77, is splined to the upright shaft 78, the lower end of it, or 35 that carrying the gear 77, being disposed in 40 a vertically movable box 76. There is also feathered to the upright shaft 78, the bevel gear 79, in mesh with the bevel gear 80, fastened to the tail-end of the feed screw 26, so that it will be clear, when said feed 45 shaft 26 is being rotated, the power necessary to effect the action of the milling feed mechanism is brought into being.

It will be clear from the foregoing description taken in connection with the annexed drawings that a machine involving the invention comprises a plurality of mechanisms operatively assembled into a single unit and each capable of performing a function different from another or others 50 of said mechanisms, and means by which any one of said mechanisms may be put individually into action or several of them into action at the same time.

These mechanisms desirably are of some 60 character of working upon metal. While as we note milling, lathe, and drill-press mechanisms answer our requirements in a highly satisfactory manner, it is not essential that we employ them all in one organization 65 and it is equally apparent that we

may combine others therewith and substitute for one or more of them, a mechanism or mechanisms otherwise functioning. The particularly important feature of the invention will of course be evident. It is 70 possible that one attendant can in a single organized machine, look after several different operations. In the structure we have especially disclosed, such individual can simultaneously take care of in a unitary apparatus milling, lathe, and drill-press operations which is a highly advantageous consideration. 75

We deem it a matter of importance to call attention to the fact, although we believe we have already made it clear, that it is in no sense necessary for us in a unitary apparatus to provide milling, lathe, and drill press mechanisms, yet obviously their association is a highly advantageous one. In the metal working machine of whatever its character may be, there is, as will be apparent, a plurality of metal working, desirably metal cutting, mechanisms, each capable of performing a function different from another 85 of said mechanisms, and each involving a work holder and a tool holder, at least one of the holders being rotary, in connection with means by which the rotary holder of a mechanism may be put individually into action or by which a plurality of the mechanisms may be put concurrently into action. Usually the metal working mechanisms which perform these different functions involve each a work holder and a tool holder, 90 one being rotary, in conjunction with means by which the rotary part of a mechanism may be individually put into action, or by which the rotary parts of several of the mechanisms may be put concurrently into 95 action. 100

From this, it will be of course clear that there may be instances where there may be only one such rotary part, although customarily there are several; that is, two or more. 110

The rotary part consists, not always, yet quite preferably, whether there be one or more of them in any organization, of a spindle. There may be conjoined with one or more of such spindles mechanism of a character entirely different from any of those to which I have specifically alluded. 115

What we claim is:

1. A metal working machine comprising a plurality of metal cutting mechanisms, 120 each capable of performing a function different from another of said mechanisms, and each involving a work holder and a tool holder, at least one of the holders being rotary, and means common to the respective mechanisms, by which the mechanism involving said rotary holder, may be individually put into action or by which a plurality of the mechanisms may be put 125 concurrently into action. 130

2. A metal-working machine comprising a plurality of metal-cutting mechanisms each capable of performing a function different from another of said mechanisms, and means by which any one of said mechanisms may be put individually into action and driven at variable speeds or several of them into action and also driven at variable speeds at the same time. 5
- 10 3. A metal-working machine comprising a plurality of metal-cutting mechanisms each capable of performing a function different from another and means by which any one of said mechanisms may be individually put into action and driven at variable speeds or two or more of them may be put into action also driven at variable speeds at the same time. 15
4. A metal-working machine comprising lathe mechanism, milling mechanism and means by which one of said mechanisms may be put individually into action independently of another or both of them into action at the same time. 20
- 25 5. A metal-working machine comprising lathe, milling, and drill-press mechanisms, and means by which any of said mechanisms may be put into action independently of the others or two or all of them into action at the same time. 30
6. A metal-working machine comprising lathe, milling and drill-press mechanisms, assembled into a unit, and means by which any one of said mechanisms may be put into individual action or all of them into action at the same time. 35
7. A metal-working machine comprising milling and drill-press mechanisms assembled in a unit, and means by which one of said mechanisms may be individually put into action or both of them into action at the same time. 40
8. A metal-working machine comprising a source of power, mechanisms each capable of performing a metal-cutting function different from another, and means by which any one of said mechanisms may be put into operative relation with said source of power to effect the action of the same independently of another or all of them into operative relation with said source of power to secure simultaneous action thereof. 45
- 50 9. A metal-working machine comprising a source of power, a plurality of mechanisms, each capable of performing a metal-cutting function different from another, and means governed at will by which any one of said mechanisms may be put into working relation with said source of power or all of them into working relation with said source of power at the same time. 55
- 60 10. A metal-working machine comprising a source of power, lathe, milling, and drill-press mechanisms, the several mechanisms and the source of power being assembled 65
- into a unit, and means by which any one of said mechanisms may be put into operative relation with said source of power or all of them into working relation with said source of power at the same time whereby one of the mechanisms may be operated alone or all of them together. 70
11. A machine of the class described comprising a source of power, a plurality of mechanisms each capable of performing a metal-cutting function different from another and assembled with the source of power into a unit, and means constituting a part of said unit, by which any one of the mechanisms may be put into driving relation with the source of power or all of them may be put into driving relation with said source of power at the same time. 75
12. A machine of the class described comprising power means, a plurality of mechanisms each capable of performing a metal-cutting function different from another and assembled with the power means into a unit, and means governed at will by which any one of said mechanisms may be put into driving relation with said power means or all of them may be put into driving relation with said power means at the same time. 80
13. A machine of the class described comprising a primary shaft, means for effecting the rotation of said shaft, two secondary shafts independent of the primary shaft, means for effecting the rotation of the two shafts from the primary shaft as desired, and mechanisms each capable of performing a metal-cutting function different from another of said mechanisms, and means whereby the mechanisms can be driven respectively from said two shafts, and means for putting either of said two secondary shafts 85 into driving relation with the primary shaft or both of them simultaneously into said driving relation. 90
14. A machine of the class described comprising a lathe spindle, a drill spindle, both assembled into a unit, and means for at will rotating either of the spindles or both of them together. 105
15. A machine of the class described comprising milling mechanism involving a spindle, lathe and milling mechanisms each having a spindle, the two latter spindles being rotative about the same axis, power operative means, and means for at will, putting either of the spindles into working relation with the power operative means or both of them concurrently into said working relation. 115
16. A metal working machine comprising a plurality of metal cutting mechanisms, each capable of performing a function different from another of said mechanisms and each involving a work holder and a tool holder, at least one of the holders being rotary, and means common to the several 120
- 125
- 130

mechanisms by which the rotary part of a mechanism may be individually put into action or by which the rotary parts of several of the mechanisms may be put concurrently into action.

17. A metal working machine comprising a plurality of metal cutting mechanisms, each capable of performing a function different from another of said mechanisms, 10 and each involving a holder, at least one of the holders being rotary, and means common to the several mechanisms, by which the rotary part of a mechanism may be individually put into action or by which a 15 plurality of the mechanisms may be put concurrently into action.

18. A machine of the class described comprising a plurality of mechanisms each capable of performing a function different 20 from another, one of said mechanisms constituting a drill-press mechanism and involving a spindle, a primary shaft, means for throwing said primary shaft into action and means between the primary shaft and 25 the spindle and operative at will, for effecting the rotation of the spindle at one of several different speeds.

19. A machine of the class described comprising a frame, a driving member inclosed 30 in said frame, milling mechanism and lathe mechanism spindles mounted upon the frame exteriorly thereof, means for at will causing the rotation of said driving member and means for transferring the effect of the 35 driving member to either of the spindles independently of the other or both of them together to cause their concurrent rotation.

20. A machine of the class described comprising drill press mechanism involving a 40 spindle, a primary shaft, means for throwing said primary shaft into action, a second shaft operatively connected with the primary shaft, means between the primary shaft and the spindle and operative at will, 45 for effecting the rotation of the spindle at one of several different speeds, milling mechanism and lathe mechanism, and means for putting the milling or the lathe mechanism into operative relation with said primary shaft to effect the action thereof.

21. A machine of the class described comprising a drill-press mechanism involving a spindle, a primary shaft, means for throwing said primary shaft into action, a second 55 shaft operatively connected with the primary shaft, means operative at will between the second shaft and the spindle, for rotating the latter at one of several different speeds, lathe mechanism and milling mechanism, means operative at will, for putting either the milling mechanism or the lathe mechanism into driving relation with said primary shaft or for putting them simultaneously into said driving relation.

65 22. A machine of the class described com-

prising a lathe spindle, a drilling mechanism spindle, and a milling mechanism spindle all assembled into a unit, and means for at will rotating any one of said spindles by power or all of them together by power. 70

23. A machine of the class described comprising a lathe spindle, a drilling-mechanism spindle, and a milling-mechanism spindle, all assembled into a single unit, a power element also in said unit, and means operable at will, for effecting the motion of any one of the spindles from said power element independently of the others or for effecting the action of two or all of them together from said power element. 75 80

24. A machine of the class described comprising milling mechanism involving a spindle, lathe mechanism involving a spindle, the two spindles being rotative about axes extending in the same direction, drill mechanism involving a spindle rotative about an axis transverse to those of the other spindles, power-operative means, and means operative at will, for putting any one of the spindles into driving relation with the power operative means or all of them concurrently into such driving relation. 85 90

25. A machine of the class described comprising milling, lathe and drill-press mechanisms each involving a spindle, power-operative means, and means operative at will, for putting any one of the spindles into driving relation with the power operative means or all of them concurrently into such driving relation and for also effecting 100 the rotation of the spindles at different speeds. 95

26. A machine of the class described comprising a frame, a plurality of mechanisms, each capable of performing a metal-cutting function different from another of said mechanisms, power-operative means inclosed by the frame, and means for at will, transferring the effect of said power-operative means to one or concurrently to more than 110 one of said mechanisms. 105

27. A machine of the class described comprising power-operative means, a shaft means for at will operating said shaft from said power-operative means, a second shaft, means for driving the second shaft from the first shaft, lathe mechanism, operative connections between the second shaft and the lathe mechanism, for effecting the action of the latter, a third shaft, connections between the first shaft and the third shaft, milling mechanism, operative connections between the third shaft and the milling mechanism, and means whereby the lathe and the milling mechanisms may be individually operated or together. 115 120 125

28. A machine of the class described comprising a shaft, power-operative means, means for at will operating said shaft from said power-operative means, a second shaft, 130

means for driving the second shaft from the first shaft, lathe mechanism, operative connections, including speed change gearing between the second shaft and the lathe mechanism for effecting the action of the latter, a third shaft, connections between the first shaft and the second shaft, connections between the first shaft and the third shaft involving speed changing mechanism, milling mechanism, operative connections between the third shaft and the milling mechanism, and means whereby the lathe and the milling mechanism may be individually operated or simultaneously.

29. A machine of the class described comprising a shaft, power-operable means, means for at will effecting the rotation of said shaft from said power-operable means, a second shaft, means for driving the second shaft from the first shaft, lathe mechanism, operative connections between the second shaft and the lathe mechanism, involving speed varying and reversing means, for effecting the action of the lathe mechanism, a third shaft, connections between the first shaft and the third shaft, milling mechanism, operative connections between the third shaft and the milling mechanism, involving speed varying and reversing means, and whereby the lathe and the milling mechanisms may be individually operated or simultaneously.

30. A machine of the class described comprising power-operable means, a shaft, means for at will, operating said shaft from said power-operable means, a second shaft, means for driving the second shaft, from the first shaft, lathe mechanism, operative connections between the second shaft and the lathe mechanism, for effecting the action of the latter, a third shaft, connections between the first shaft and the third shaft, milling mechanism, operative connections between the third shaft and the milling mechanism, drill press mechanism, operative connections between the first shaft and the drill-press mechanism, and means whereby the lathe, the milling, and the drill-press mechanisms may be individually or simultaneously operated.

31. A machine of the class described comprising lathe mechanism involving a carriage, milling mechanism involving a carriage, power-operable means, all assembled in a single unit and means for at will operating either carriage from said power-operable means, or both of them simultaneously from said power-operable means.

32. A machine of the class described comprising lathe mechanism involving a carriage, milling mechanism also involving a carriage, drill press mechanism involving a spindle, power-operable means, all of them assembled in a single unit, and means operable at will, for operating either carriage

or the spindle from said power-operable means individually, or all of them simultaneously from said power-operable means.

33. A metal-working machine comprising different kinds of mechanisms, each involving a carriage and each adapted to function differently from another, power-operable means, the mechanisms and the power-operable means being assembled into a unitary structure, and means for at will 70 operating either carriage from said power-operable means or more than one of them simultaneously from said power-operable means.

34. A metal-working machine comprising 80 lathe mechanism involving a reciprocating carriage and a spindle, milling mechanism involving a reciprocating carriage and a spindle, both assembled operatively into a common unit, power operable means also 85 constituting part of said unit, and means for at will causing the concurrent rotation of the spindle and the travel of the carriage of the lathe mechanism and at the same time the concurrent rotation of the spindle and 90 the travel of the carriage of the milling mechanism from said power-operable means.

35. A metal-working mechanism comprising two mechanisms capable of performing different functions upon stock and 95 each of them comprising a spindle and a reciprocating carriage, power-operable means, the latter and the two mechanisms being assembled operatively into a single unit, and means for causing at will from 100 said power-operable means the simultaneous rotation of both spindles and the travel of the carriages.

36. A metal-working machine comprising lathe, milling and drill-press mechanisms, 105 each involving a spindle, and the milling and the lathe mechanisms each involving a traveling carriage, the three mechanisms being assembled into a single operative unit, power-operable means also constituting a 110 part of said unit, and means for at will, causing from said power-operable means, the rotation simultaneously of the three spindles and the travel of both carriages.

37. A metal-working machine comprising 115 lathe, milling and drill-press mechanisms each involving a spindle, and the milling and the lathe mechanisms each involving a traveling carriage, the three mechanisms being assembled into a single operative unit, 120 power-operable means also constituting a part of said unit, and means for at will, causing from said power-operable means, the rotation simultaneously of at least two of the spindles and the travel of both the 125 carriages.

38. A metal-working machine comprising milling mechanism and lathe mechanism each involving a spindle said mechanisms being assembled into a common unit, 130

and the spindles being coaxial, a power-operable member supported by the coaxial spindles, and mechanism, for at will, transferring the effect of said power-operable member to said spindles for concurrently rotating the same.

39. A metal-working machine comprising milling mechanism and lathe mechanism assembled into a common unit and 10 each involving a rotary spindle and a traveling carriage, a power-operable means constituting part of said unit, the two spindles being coaxial and jointly supporting said power-operable member, and means for at 15 will, transferring the effect of said power-operable member simultaneously to both spindles for rotating the same and to both carriages for moving the same.

40. A metal-working machine comprising 20 milling, lathe and drill-press mechanisms, the milling and the lathe mechanisms each involving a carriage and a spindle in correlation with each other and the drill-press mechanism involving a spindle, a 25 source of power, the three mechanisms and the source of power being assembled into a single unit, and means operable by the attendant of said machine, for causing the 30 simultaneous rotation of the three spindles and the movement of the two carriages, from said source of power.

41. A metal working machine comprising 35 a plurality of metal cutting mechanisms, each capable of performing a function different from another of said mechanisms, and each involving a rotary spindle, and means common to the several mechanisms, by which the rotary part of a mechanism may be individually put into action 40 or by which the several spindles may be concurrently put into action.

42. A metal working machine comprising 45 a plurality of metal cutting mechanisms, each capable of performing a function different from another of said mechanisms, at least one of the mechanisms involving a rotary spindle, and means common to the several mechanisms, by which 50 said mechanisms may be individually put into action or by which the several mecha-

nisms may be concurrently put into action, the spindle rotating when the mechanism involving it is in action and also rotating when the several mechanisms are concurrently in action.

43. A metal working machine comprising 55 a plurality of metal working mechanisms, each capable of performing a function different from another of said mechanisms, and each involving a work holder and a tool holder, at least one of the holders being rotary, and means common to the several mechanisms, by which the mechanism involving said rotary holder may be 60 individually put into action or by which a plurality of the mechanisms may be 65 concurrently put into action.

44. A metal working machine comprising 70 a plurality of metal working mechanisms, each capable of performing a function different from another of said mechanisms, at least one of the mechanisms involving a holder which is rotary and has 75 means for gripping a part, and means common to the several mechanisms by which the mechanism involving said rotary holder may be 80 individually put into action or by which a plurality of the mechanisms may be 85 concurrently put into action.

45. A metal working machine comprising 85 a plurality of metal working mechanisms, each capable of performing a function different from another of said mechanisms, at least one of the mechanisms involving holders, one of which is rotary, 90 one of the holders acting to grip a tool and the other to grip a piece of work, and means common to the several mechanisms, by which the mechanism involving said holders may be put individually into action during 95 which one of the holders rotates, or by which a plurality of the mechanisms may be concurrently put into action.

In testimony whereof we affix our signatures in the presence of two witnesses.
